UNITED STATES PATENT OFFICE.

PHILIP E. EBRENZ, OF ST. LOUIS, MISSOURI, ASSIGNOR TO JOHN DEERE
PLOW COMPANY, OF ST. LOUIS, MISSOURI, A COPARTNERSHIP.

DASH-FOOT AND TOE-RAIL SUPPORT FOR VEHICLES.

No. 825,640.

Specification of Letters Patent.

Patented July 10, 1906.

Application filed October 23, 1905. Serial No. 283,926.

To all whom it may concern:

Be it known that I, PHILIP E. EBRENZ, a citizen of the United States, residing in the city of St. Louis and State of Missouri, have 5 invented certain new and useful Improvements in Dash-Foot Members and Toe-Rail Supports for Vehicles, of which the following is a full, clear, and exact description, reference being had to the accompanying drawings, forming part of this specification.

My invention relates to a device for attaching dashes to the bodies of vehicles, such as buggies and carriages, and for supporting the toe-rails.

15 One of the objects of my improvement is to provide a device of the character named of such construction that the dash of the vehicle is firmly and rigidly connected to the vehicle-body and braced to resist any strain to 20 which it may be subjected.

Another object is to provide for the rigid support of the toe-rail by securing it to the dash-foot members, which are in turn fastened to both the side sills and forward corner-posts of the vehicle-body.

Figure I is a perspective view of part of a frame of a vehicle-body with my improvement shown applied thereto. Fig. II is an enlarged perspective view of one of the front 30 corners of a vehicle-body and a portion of the dash to be applied thereto shown separated from said body. Fig. III is an enlarged vertical section taken through the joint of one of my brackets. Fig. IV is a 35 side elevation of a modification of my improvement.

A designates the body of a vehicle having side sills B, a forward cross-sill C, and corner-posts D.

40 1 designates foot members of brackets having their feet 2 secured to the side vehicle-body sills B by screws 3 or other suitable means of fastening. The feet of these foot bracket members are seated upon the side sills 45 remote from the vehicle-body front corner-posts, and the members extend upwardly from their feet at an angle to said corner-posts to points 4 and vertically from the points 4 and are secured to the corner-posts 50 by bolts 5 or other suitable means of fastening. By this construction and arrangement of the bracket foot members they are caused to efficiently connect the front corner-posts to the side sills of the vehicle-body and resist

strain against said posts. The foot members 55 terminate at their upper ends in socket-heads 6, in which the cavities 7 are preferably circular. The cavity in each socket-head extends inwardly from the front end of the head, and in each head between the base 60 of the socket-cavity and the rear side of the socket-head is a bolt-hole 8.

E designates the dash of the vehicle, which may be of any common form.

9 represents dash bracket members arranged parallel with the dash in vertical lines and which are secured to the frame of the dash at their upper ends intermediate of the bottom and top of the dash and at approximately the vertical center of the dash by 70 bolts 10. Each dash bracket member 9 is provided with a stem 11 extending rearwardly from its lower end and adapted to seat in the socket-cavity 7 of the corresponding foot-bracket-member socket-head 6. In 75 each of the stems 11 is a longitudinally-extending bolt-hole 12.

13 represents bolts which pass through the bolt-holes 12 and 8 in the dash-bracket-member stems and foot-bracket-member socket-heads, as seen in Fig. III, whereby said parts are detachably united to provide for their assemblage and connect the dash to the vehicle-body or permit of the disconnection of the dash from the body. The bolts 13 pass 85 through the lower portion of the dash E, as seen in Fig. III.

It will be seen that by the construction of the dash-support as described, in which the dash bracket members 9 are arranged parallel with the dash in vertical lines and secured to the dash at both its bottom and at points intermediate between the bottom and top of the dash, said bracket members serve to efficiently brace the dash against lateral 95 movement and resist all ordinary strain that may be exerted thereagainst, such as by a person pressing against it in entering or leaving the vehicle and using it as a handhold, as is commonly done.

14 designates a toe-rail which is secured to the foot members 1 of the brackets by bolts 15, whereby the brackets that support the dash have additional utility of serving as supports for said toe-rail. By attaching the toe-rail to the foot bracket members, which are in turn fastened to both the side sills and the front corner-posts of the vehicle-body, said

2
toe-rail is firmly and rigidly supported, due to the manner of attachment of the bracket foot members to the body, and as a consequence of such arrangement force exerted 5 against the toe-rail is not transmitted to the corner-posts, with a result of strain thereagainst, this fact being due to the bracket foot members being rigidly held to the side sills B.

16 The foot bracket members 1 consist of adjustable sections, as seen in Fig. II, and these sections are secured from movement independent of each other by any suitable means, such as a bolt 16, that unites the parts of the 15 member that preferably telescope one within the other. The advantage of this adjustable construction of the foot bracket member is that of providing for the application of the member to bodies of vehicles in which the corner-posts D vary in height, thereby necessitating the use of foot bracket members of varying lengths.

16 In Fig. IV I have shown a modification wherein the members 1^a and 9^a of my dash 25 and toe-rail supporting brackets are made integral with each other instead of being in the form of separate sections. In this modification the configuration of the brackets is similar to the configuration of the brackets previously described, and the dash is removably 30 connected to the brackets by the bolts 10^a and 13^a. The toe-rail 14^a is secured to the foot portions of the brackets in this modified 35 form in a manner similar to its attachment to the like members as previously described.

I claim as my invention—

1. The combination with a vehicle-body

and its dash, of brackets having foot members secured to said body and provided at their upper ends with socket-heads, and 40 brace members arranged parallel with the dash and extending from the bottom of the dash to points intermediate of its bottom and top, the brace members having stems to enter said socket-heads; and means for securing 45 said stems in said socket-heads and the upper ends of said bracket brace members to said dash, substantially as set forth.

2. The combination with a vehicle-body 50 and its dash, of dash-supporting brackets secured to said body and dash, and consisting of lower sections arranged obliquely to said dash and upper sections arranged parallel with said dash and adjustably fitted to said lower sections, and means whereby said 55 bracket-sections are united, substantially as set forth.

3. The combination with a vehicle-body and its dash, of dash-supporting brackets secured to said body and said dash, and consisting of sections telescopically fitted to each other, and means whereby said bracket-sections are adjustably united, substantially as 60 set forth.

4. The combination with a vehicle-body 65 and its dash, of dash-supporting brackets secured to said body and said dash, and consisting of sections telescopically fitted to each other, and bolts connecting said bracket-sections, substantially as set forth.

PHILIP E. EBRENZ.

In presence of—

BLANCHE HOGAN,

Wm. H. SCOTT.
